PRESSING MACHINE WORK SUPPORT
POSITIONING MEANSGeorge R. Bicknell, Antioch, Ill., assignor to
The American Laundry Machinery Company,
Norwood, Ohio, a corporation of Ohio

Application April 9, 1937, Serial No. 135,908

4 Claims. (Cl. 38—22)

This invention relates to improvements in pressing machines, and more particularly to apparatus for automatically placing a pressing member in suitable position for dressing work upon it, followed by automatic movement of the member to a pressing position.

In certain types of pressing operations it is difficult for the operator to dress laundered articles, garments and the like in position upon a pressing bed or buck or other work support if that support is in a horizontal position, as is customary in many types of pressing machines. In such case, it is advantageous to tip or tilt the pressing bed or work support so as to make the work dressing operation easier. My present invention provides novel apparatus for accomplishing this purpose.

One of the features of my invention is the provision of a pressing machine having a plurality of work supports which are moved to position one of the supports for coaction with a pressing member in a pressing operation while moving the other work support to an open position at a dressing station where work is arranged upon the support. My invention provides in such a machine novel means for tilting the work support at the dressing station into position for more readily arranging work upon it.

My invention also provides a pressing machine having a single pressing head and a pair of work supports movable alternately to place one support in registration with the pressing head and the other support in open position before an operator. With this type of machine I provide novel interconnecting means whereby the movement of the work support in pressing position into engagement with the pressing head at the same time tilts the work support in open position so as to aid the operator in dressing work upon it. My invention also includes the return of the support in open position to a horizontal or untilted position upon opening the press.

Other novel features of my invention will be apparent from the accompanying specification and drawing and the essential features thereof will be summarized in the claims.

In the drawing, Fig. 1 is a front elevation of a pressing machine embodying my invention; Fig. 2 is a sectional plan view along the line 2—2 of Fig. 1; while Fig. 3 is a fragmental side elevation of the left-hand work support member of Figs. 1 and 2, showing the work support in tilted position.

While my invention is applicable to different types of machines, I have chosen to illustrate the

same as applied to a laundry or garment pressing machine of the turret type, as fully illustrated described and claimed in Patent No. 1,997,219 granted April 9, 1935 to Oscar W. Johnson.

This pressing machine comprises a fixed frame portion 10 supporting a chest 11 which may be heated in any well known manner, and a rotatable frame portion 12 carrying a pair of pressing beds or work supports 13 and 14. One of these pressing beds is movable by frame rotation into registration with the head 11, while the other pressing bed is simultaneously moved to an open position adjacent an operator for placing work upon or removing work from that bed. The beds are arranged for vertical movement relative to the rotatable frame by means of the pressure pins 15 and 16 depending from the beds through suitable bores in the frame in position to register with and to be raised by the rod 17 of piston 18 which is enclosed in a suitable cylinder 19 in the stationary frame portion 10. In such a press the frame may be rotated by hand but I have illustrated the power mechanism for rotating the frame and causing pressure engagement of the registering pressing members as provided in the press of the above mentioned Johnson patent and further reference may be had to this patent for a complete description.

It will be sufficient for the present purpose to state that air for the operation of piston 18 is supplied through conduit 20 and controlled by inlet valve 21 and outlet valve 22, the exhaust being by way of conduit 23. The valve stems are connected to an operating lever 24 as shown in Fig. 1, which lever is pivoted intermediate its ends to the frame 10 and is actuated by means of pedals 25 and 26. These pedals are interconnected so that when one is moved downwardly the other moves upwardly. Movement of pedal 25 downwardly causes air to be supplied beneath piston 18, raising rod 17 and the pressure pin 15 of a registering bed so as to cause a closing of the press. Mechanism indicated generally at 27 comprises a frame or turret rotating device for causing rotation of the frame 12. This is a spring operated device cocked upon upward movement of piston 18 and released upon downward movement of the piston, whereupon the device 27 rotates the frame 12 through 180°, reversing the position of the pressing beds. A block 28 spring pressed upwardly engages one of the members 29 to hold the frame 12 in indexed position. After the press has been closed, as previously described, by depression of pedal 25, upon the completion of a pressing operation

- pedal 26 is depressed which reverses the position of valves 21 and 22 and at the same time withdraws the block 28 from the member 29. Air is evacuated from beneath piston 18, the bed in pressing position drops and the device 27 rotates the frame 180° carrying the bed which was formerly in open position into registration with the head 11. Upon the next depression of pedal 25 another pressing operation takes place. An interlocking pin 30 enters an opening in flange 31 which is rigid on the frame 12 and prevents depression of pedal 25 except when the pin 30 has entered notch 31 insuring that a bed is in registration with the pressing head.
- 15 In the above machine which is old, I provide a novel arrangement for tilting the pressing bed in open position to facilitate the dressing of work upon it. To this end, each pressing bed comprises a substantially horizontal base portion 32 and a tilttable workholding portion 33 hinged to the base portion at 34. For the pressing of shirts and the like the portion 33 may be a board provided with padding. In this particular type of press I provide a board for pressing shirts by 25 "double lay", meaning that the shirt is placed directly on the board 33 so that both front and back portions of the shirt are pressed in one operation. The board is made large to accommodate shirts of any size and it is therefore difficult 30 for the operator to reach all parts of the board when in its horizontal position.
- The means for automatically raising the board 33 to tilted position comprises a lever 35 pivotally connected to the frame 12 at 36 and having its 35 free end connected by a rod 37 with the bracket 38 of board 33. This connecting rod 37 has a swiveling movement with bracket 38 and may be adjusted at its point of connection with lever 35. Lever 35 also has an ear 39 through which 40 freely passes a rod 40 having a universal connection 41 with the bed 13. The lower end of rod 40 is provided with an adjusting nut and a lock nut. Similar parts are provided for the other pressing bed, such parts being given similar reference 45 characters with the suffix "a".
- With the parts in the position of Figs. 1 and 2, it will be obvious that as the pressing bed 13 with work placed upon the upper portion 33a thereof, is raised into engagement with the head 11, rod 50 40 will lift lever 35, thus raising the board 33 of the pressing bed 14 about its hinge connection to the tilted position shown. By the proper adjustment of the parts, the angle of tilt may be adjusted as desired. With the parts in this position the operator arranges the lay of the work upon the pressing bed 14 and then depresses pedal

26. This causes bed 13 to drop as previously described and this automatically returns the board 33 to the dot-dash position of Fig. 3, whereupon the frame 12 rotates and carries the bed 14 into pressing position. Upon depression of pedal 25 5 bed 14 rises into engagement with head 11 and rod 40a will lift lever 35a to tilt the board 33a for the dressing of work thereon.

What I claim is:

1. In a pressing machine, a pressing head, a 10 pair of work supports movable to place one in position for a pressing operation in coaction with said head while placing the other work support in work dressing position, each support comprising a base and a work holder movable relative 15 thereto, and means for coincidentally causing a pressing operation between said head and said work support in pressing position and for causing a movement of the work holder relative to its base of said work support in dressing position. 20

2. In a pressing machine, a pressing head, a plurality of pressing beds, means for moving one of said beds into pressing position for coaction with said head while moving another bed to a work dressing station, operating means for causing a pressing operation between said pressing head and a bed in pressing position, and means actuated by said operating means for tilting a bed at said dressing station. 25

3. In a pressing machine, a pressing head, a 30 plurality of pressing beds, means for moving one of said beds into pressing position for coaction with said head while moving another bed to a work dressing station, operating means for causing relative approach and separating movement 35 between said head and a bed in pressing position, and an operative connection between said operating means and a bed at said dressing station arranged for tilting such bed into and out of work dressing position coincidentally with said approach and separating movements respectively. 40

4. In a turret press, a pressing head member, a rotatable frame, a pair of pressing bed members movable by frame rotation, one into registration beneath said head member and the other into 45 open position at a work dressing station, each bed member comprising a base portion and a tilttable portion, means for raising and lowering said registering bed member into and out of pressing engagement with said head member, and an 50 operative connection between said means and the tilttable portion of said bed member in open position for raising and lowering the said tilttable portion by bed member raising and lowering movements respectively of said means. 55

GEORGE R. BICKNELL.
